UNITED STATES PATENT OFFICE.

JOHN J. LYNCH, OF MCKEES ROCKS, PENNSYLVANIA.

RAIL-JOINT.

1,054,429.

Specification of Letters Patent.

Patented Feb. 25, 1913.

Application filed December 18, 1912. Serial No. 737,445.

To all whom it may concern:

Be it known that I, JOHN J. LYNCH, a citizen of the United States of America, residing at McKees Rocks, in the county of 5 Allegheny and State of Pennsylvania, have invented certain new and useful Improvements in Rail-Joints, of which the following is a specification, reference being had therein to the accompanying drawing.

10 This invention relates to rail joints, and the primary object of my invention is to obviate the necessity of using bolts and nuts as a fastening means for connecting splice bars or fish plates to the sides of rails to 15 connect said rails and maintain the same in longitudinal alinement.

Another object of this invention is to provide simple and effective means for connecting splice bars to the base flanges of 20 rails whereby the rails cannot become accidentally displaced.

25 A further object of this invention is to provide a rail joint that is durable, easy to install, and highly efficient as a connection between the abutting or confronting ends of rails.

With the above and other objects in view the invention resides in the novel construction, combination, and arrangement of parts 30 to be hereinafter specifically described and then claimed.

Reference will now be had to the drawing, wherein:—

Figure 1 is a side elevation of the rail joint partly broken away and partly in section, Fig. 2 is a bottom plan of the same, Fig. 3 is a cross sectional view taken on the line III—III of Fig. 1, and Fig. 4 is a similar view taken on the line IV—IV of 40 Fig. 1.

Further describing my invention in detail with reference to the accompanying drawing, wherein like numerals denote corresponding parts throughout: 1 denotes the 45 abutting or confronting ends of rails that have the base flanges 2 thereof provided with L-shaped slots 3, the long arms 4 of said slots extending longitudinally of the base flanges, and the outer wall of each

slot has a depending tapering or beveled enlargement 5, the object of which will presently appear.

6 denotes splice bars for engaging and bracing the outer sides of the rails 1 and these splice bars are provided with depending tongues 7 having transversely disposed heads 8. The tongues 7 are adapted to extend through transverse portions of the slots 3 and by shifting said splice bars, the heads 8 of said tongues riding under the 60 enlargements 5, the taper or bevel of said enlargements drawing the splice bars 6 into snug engagement with the rails.

The outer edges of the splice bars are enlarged, as at 9 whereby spikes or other 65 fastening means can be resorted to for securing the splice bars and rails to ties, sleepers or other supports after said splice bars have been adjusted to firmly hold and lock the rails together.

One embodiment of my invention has been illustrated, but it is to be understood that the structural elements are susceptible to such variations and modifications as fall within the scope of the appended claim.

What I claim is:—

In a rail joint, the combination of rails having the base flanges thereof provided with L-shaped slots with the long arms of said slots extending longitudinally of said 80 rails and the outer walls of said slots provided with depending tapering enlargements, splice bars bracing the sides of said rails, depending tongues carried by said splice bars and extending into the L-shaped 85 slots of said rails, and transverse heads carried by said tongues and adapted to be shifted into engagement with the enlargements of the base flanges of said rails whereby said splice bars are held in snug 90 engagement with said rails.

In testimony whereof I affix my signature in the presence of two witnesses.

JOHN J. LYNCH.
